UNITED STATES PATENT OFFICE.

EDWIN C. VAN NOUHUYNS, OF ALBANY, AND KYRAN C. DOWNES, OF GREENBUSH, NEW YORK.

FAN ATTACHMENT FOR BABY-CARRIAGES.

SPECIFICATION forming part of Letters Patent No. 399,585, dated March 12, 1889.

Application filed March 5, 1887. Renewed January 16, 1889. Serial No. 296,570. (No model.)

To all whom it may concern:

Be it known that we, EDWIN C. VAN NOUHUYNS, of the city and county of Albany, and KYRAN C. DOWNES, of Greenbush, in the county of Rensselaer, both in the State of New York, have invented new and useful Improvements in Fan Attachments for Baby-Carriages, of which the following is a specification.

10 Our invention relates to automatic fan attachments for baby-carriages; and it consists of the combination of parts herein described for rotating a fan by the rotative motion of the wheels of a vehicle.

15 In the accompanying drawings, which are herein referred to and form part of this specification, Figure 1 is a perspective view of a baby-carriage provided with our attachment, and Fig. 2 a front elevation of our fan attachment detached from the carriage.

As represented in the drawings, A is the baby-carriage, which may be of any preferred style and form; and B, the wheels on which it runs.

25 It must be understood that our invention has no relation to the construction of the carriage, and, as shown in the drawings, all parts of it are old and well known.

Our fan attachment consists of the following parts: A bracket, C, which is secured to the body of the carriage by a bolt, c, so that it can be readily detached therefrom if required, or thrown over sidewise when the fan is not required to revolve. Said bracket has near 35 its upper end a lateral arm, 1, which forms a journal-bearing for a shaft, D. Near the lower end of said bracket is a lateral socket, 2, in which a sliding stud, 3, is inserted to form a bearing for the lower end of the shaft 40 D, and a spring, 4, is fitted in said socket to bear against the inner end of the sliding stud 3, so as to force the latter outwardly. The shaft D has a friction-wheel, 5, secured to it, and said wheel is pressed by the spring 4 against the inner side of one of the carriage-wheels B, so that as the carriage - wheel revolves a rotatory motion will thereby be imparted to the shaft D. A horizontal shaft, E, is journaled in the upper end of the bracket 45

50 C, and in a branch or arm, 6, of said bracket a pair of bevel-wheels, either toothed or frictional, is secured on the adjacent ends of the shafts D and E, so that the two will have a uniform motion. When frictional wheels are

used, springs 7 should be interposed between the back of each wheel and the journal-bearing nearest to it for the purpose of forcing said wheels into frictional contact with each other. A fan, F, is secured to the inner end of the shaft E, so as to bring it about centrally over the body of the carriage, when, as the fan is revolved, it will deliver a current of air fairly upon the occupant of the carriage. A spring-catch, 8, is fixed to the bottom of the bracket C, and is arranged to engage with the shaft D and hold the friction-wheel 5 out of contact with the carriage-wheel when it is desired to stop the fan F from revolving, and the bracket C can be turned sidewise on the bolt c into a position 70 where it will be out of the way of placing a child in the carriage.

By providing a sliding stud for the bearing at the lower end of the shaft D we are enabled to obtain a constant pressure of the 75 friction-wheel 5 against the side of the wheel B, notwithstanding any little irregularity that may exist in the side of the rim of said wheel.

We claim as our invention—

1. The combination, with a baby-carriage 80 and its supporting-wheels, of a bracket secured to said carriage and forming the bearings for the fan-actuating shafts; a vertical shaft provided with a friction - wheel which bears against a wheel of said carriage and is 85 held in frictional contact with said wheel by means of a spring-bearing, and a horizontal shaft which is connected by gearing to the vertical shaft and has a series of fan-blades attached thereto, as and for the purpose specified.

2. A fan attachment for baby-carriages, consisting of a bracket having journal-bearings for a horizontal and a vertical shaft formed therein, the lower bearing for the latter being forced outwardly by a spring, and said vertical shaft having a friction - wheel that is arranged to bear against one wheel of the carriage, the said horizontal shaft being geared to the vertical shaft and having blades 95 for a rotary fan attached thereto to extend over the body of the carriage, as and for the purpose herein specified.

EDWIN C. VAN NOUHUYNS.
KYRAN C. DOWNES.
